CHARLES V. WALTER, OF BRONXVILLE, NEW YORK

GRINDING MACHINE

Application filed August 28, 1929. Serial No. 388,883.

This invention relates to grinding machines, more particularly to machines for grinding, beveling or polishing the edges of watch crystals, lenses, and similar glass disks or bodies.

One object of my invention is to provide an improved machine of this character, particularly one which is automatic in its operation. A further object of my invention is to provide an improved machine for grinding a bevel at the edge of the lens or disk by a series of grinding operations or steps, all of which steps are performed automatically and require little or no attention on the part of the operator.

A further object of my invention is to provide a machine of this character wherein the succession of steps required for the grinding operation are electrically controlled, as will be more fully described hereafter.

A further object is to provide a machine of this character which is adapted to grind a number of lenses or disks simultaneously. A further object is to provide a glass grinding machine which will grind a plurality of glass disks or lenses of different size simultaneously.

A still further object is to provide a glass beveling machine of this character with an improved means whereby the angle of bevel may be changed as desired, and particularly where such angle may be changed or varied over a relatively wide range.

A further object of my invention is to provide an improved means for holding the lenses or other glass disks during the operation of grinding.

A further object of my invention is to provide an improved means for automatically feeding the lens to the lens holder and automatically discharging it when the grinding operation has been completed.

A further object of my invention is to provide an improved polishing wheel which is adapted to polish a bevel at the edge of a glass disk and at the same time to round off one edge of the beveled surface so as to prevent the formation of sharp corners or acute angles at the edge of the disk.

Further objects and advantages of my in-

vention include simplicity of construction, economy of time and efficiency of operation, ease with which the various steps of grinding may be controlled and the several adjustments made, and the superiority and uniformity of the product produced.

Other objects and advantages of my invention will appear from the following description taken in connection with the accompanying drawings, wherein:

Figure 1 is a side elevation, partly in section and partly broken away, of a grinding machine showing one embodiment of my invention;

Figure 2 is a fragmentary top plan view of the structure shown in Figure 1;

Figure 3 is a horizontal sectional view looking upward, taken on the line 3—3 of Figure 1;

Figure 4 is a detail view partly in elevation and partly in section, certain of the parts shown being in section on the line 4—4' of Figure 2;

Figure 5 is an enlarged detail view of part of the structure shown in Figure 4;

Figure 6 is a diagrammatic view of the electrical control for the mechanism employed to shift the grinding wheels to bring different wheels into position for grinding the lens;

Figure 7 is a top plan view of a portion of the finishing or polishing wheel, showing an improved construction for rounding off the sharp edges of the disk or lens as it is being beveled; and

Figure 8 is a detail horizontal sectional view of the structure shown in Figure 7.

Referring to Figure 1 of the drawings, the machine comprises supporting frame 1, the top of which is formed as a table 2. Secured to a vertical shaft 6 extending upwardly through the table 2 are three grinding wheels A, B and C, which are designed to operate on the edge of the lens successively, wheel A being a wheel of relatively rough or coarse composition for making the initial beveling cut; wheel B of a finer composition, and wheel C having an outer surface of felt or similar material required for the finishing operation.

In Figure 2 I show four lens or disk holder assemblies, 10, 11, 12 and 13, respectively, arranged around the peripheries of the grinding wheels, these several work or lens holder assemblies being adapted to hold lenses or disks 15 against the particular grinding wheel which at the time is performing its grinding operation.

Each lens holder assembly comprises two lens holders 21, located at diametrically opposite points, these lens holders being carried by a lens holder assembly head 20, which is mounted to rotate about a central vertical axis 21', means being provided which constantly tends to rotate the lens holder head in a counter clockwise direction as viewed in Figure 1, as will be more fully explained hereafter.

At 50 in Figure 2 I show supply hoppers or chutes adapted to contain lenses or other disks to be ground and at 51 I show discharge chutes adapted to receive the lenses which have been ground, one supply and one discharge chute cooperating with each lens holder. In the position of the parts shown in Figure 2 a lens which has been ground has been discharged into the chute 51 from the outer one of the two lens holders shown in the lens holder assembly, the inner lens holder 21 has taken a new lens from the supply chute 50 and the lens holder assembly has been rotated in a counter clockwise direction so as to bring the new lens into contact with one of the grinding wheels. The first grinding wheel to grind the lens is the bottom wheel A. After a predetermined number of grinding revolutions, the shaft 6 which carries the grinding wheels is moved downward so as to move the middle wheel B into position for engagement with the lens. Again after a predetermined number of revolutions, the shaft 6 is again moved downward so as to bring the finishing wheel C into position for engagement with the lens. Again after a predetermined number of revolutions the shaft 6 is raised so as to move all of the grinding wheels above the lens holder and the lens holder assembly is rotated through an angle of somewhat less than 180° about the axis 21' to such a position that the lens 15 which has been ground is over the discharge hopper 51 and the lens holder 21 at the opposite end of the assembly has been moved to the supply chute 50 to receive a lens from the chute. The raising of the wheel permits the lens holder assembly to rotate beneath the wheels to this position and while in this position the finished lens is discharged into the chute 51 and a new lens taken from the supply chute 50. While the lens holders are at the supply and discharge chutes, the shaft 6 is lowered so as to bring the first grinding wheel A into position for engagement with the new lens. The lens holder assembly then rotates in a

counter clockwise direction until the new lens is brought into contact with the grinding wheel A, from which time the cycle of operations above described is repeated.

In this description of the cycle of operations I have referred to but one of the lens holder assemblies. It will, however, be understood that each of the four or more lens holder assemblies will be simultaneously moved in a similar way and each will serve to hold its own lens against the grinding wheel which at that particular time is performing the grinding operation.

Lens holder assembly

In Figure 4 I show in detail one of the lens holder assemblies. This assembly comprises a rotatable lens holder head 20 which carries two lens holders 21, extending outwardly from diametrically opposite points of the head. Each lens holder assembly is mounted on a vertical shaft 22 which constantly rotates in a counter clockwise direction as viewed in Figure 2.

Each lens holder comprises tubular casings 30 in which is slidably and rotatably fitted a hollow cylindrical member or sleeve 32, formed with a shoulder 33 between which and the outer end of the casing 30 is a piston 35 which extends inwardly of the assembly head and projects through an opening 38 formed in a gear wheel 39, mounted to project into and rotate in the casing 30. Interposed between collar 37, secured to the piston rod and an inwardly projecting annular portion 40 of the sleeve 32 is a helical compression spring 42. Seated in the outer end of the tube 32 is a lens holding member or nozzle 44 which may be formed of rubber or other relatively soft material to form a cushion seat for the lens. Member 44 is formed with a circular opening which communicates with the interior of the sleeve 32.

In operation the lens 15 is held against the seat 44 by suction. Spring 42 normally forces the piston 35 inwardly and creates sufficient suction to hold the lens. Means is provided for sliding the piston 35 outwardly through the sleeve 32 when it is desired to release a lens from the holder and for permitting the spring 42 to move the piston inwardly when it is desired to apply suction to hold the lens on its seat. Motion of the piston outwardly from the position shown in Figure 4 has the effect first of relieving the suction on the lens holder. Continued movement of the piston causes it to engage the shoulder 33 of the sleeve 32 and still further outward movement of the piston causes the sleeve and lens holding member 44 to move outward, thereby compressing the spring 34 located between the sleeve 32 and casing 30. Spring 42 is considerably stronger than spring 34 and when the piston 35 and sleeve 32 are released so as to be moved under the

influence of the two springs, the retraction of the piston 35 takes place more rapidly than retraction of the sleeve 32, thereby creating considerable suction before any substantial retractive movement of the sleeve 32. This is to permit the suction nozzle 44 after it has been advanced into engagement with a lens at the bottom of the hopper 50 to take hold of the lens before the nozzle is moved to its retracted position. It is obvious that if desired I may provide means for positively holding the nozzle in its advanced position until suction has been applied, as, for example, by means of a catch between the sleeve 32 and casing 30, which catch is released only after a predetermined retractive movement of the piston 35 in the sleeve 32.

The releasing of one lens and the grasping of another lens, respectively, is performed by simultaneously moving their respective pistons first outwardly and then inwardly. For this purpose I provide a vertical rod 52 which is slidable in the shaft 22. The upper end of the rod 52 is loosely secured to the short arms 55 of bellcrank levers 56, pivoted at 57 to the lens holder head 20. The longer arms 60 of the bellcrank levers 56 are adapted to move outwardly and engage the inner ends of the respective pistons 35.

It will be seen that upon moving the slidable rods 52 downwardly, the long arms 60 of the bellcrank levers are moved outwardly and engage the inner ends of the pistons, moving the pistons outwardly through the sleeves 32. This movement of the piston at the left of Figure 4 serves to relieve the pressure inside the sleeve 32 with the result that the lens 15 drops off from the seat 44 into any suitable receiving chute or hopper, 51. The continued downward movement of the rod 52 causes the pistons 35 to engage the shoulders 33 of the sleeves 32 in each lens holder and further movement of the rod 52 downwardly causes

each suction nozzle 44 to move outwardly a short distance from its respective casing 30. This outward movement of the nozzle 44 at the right of Figure 4 causes this nozzle to engage a lens 15' lightly held at the bottom of the chute 50 by springs 64 and on the subsequent raising of the rod 52 and withdrawal of the arms 60 from the ends of the pistons, permits the springs 42 to move the pistons backwardly in the sleeves 32, thereby causing suction to be applied to the unground lens 15' so that this lens is held against the seat 44. Also, spring 34 serves to retract the seat 44, which carries with it the lens 15'.

It will thus be seen that as a result of the operations just described a finished lens has been discharged from the holder at the left hand of Figure 4 and a new unground lens has been received by the lens holder at the right of this figure.

Drive

The machine is driven from an electric motor 100 which is connected to a shaft 101 having at one end a bevel gear 104 which meshes with a gear 105 splined to the vertical shaft 6, which carries the grinding wheels A, B and C. Shaft 6 is rotated by the gear 105 and is adapted to move vertically through the gear when the grinding wheels are shifted from one position to another. Also splined to the shaft 6 and adapted to be turned thereby is a gear 110 which meshes with four gears 112, supported beneath the table 2 at points equally spaced around the axis of the shaft 6. Each of the gears 112 serves to drive a gear 114, also supported beneath the table 2. One of the gears 114 is shown in Figure 4. Each of the gears 114 is rotatable on stationary bearing shaft 116 which extends through the table 2 and is secured in position by a screw 117 which is screw-threaded through a bushing 118, projecting downwardly from the bottom of the table. Gear 114 is held on the stationary shaft 116 by means of a nut 120.

Surrounding the upper end of shaft 116 is a collar 122 which forms one end of an arm 123. The other end of the arm 123 is formed with a bearing sleeve or collar 125 which projects downwardly through an arcuate slot 126 in the table 2. The top of the table is formed with a seat 127, the upper surface of which is accurately machined so as to form a firm support for the bearing sleeve 125. Rotatably mounted in the sleeve 125 is the shaft 22 which carries at its upper end a gear 130 which meshes with the gears 39 and serves to rotate the sleeve 32 and the lens holding nozzles 44. Secured to the lower end of the shaft 22 is a gear 132 which meshes with the gear 114 and is driven thereby.

Gear 132 is driven in a counter clockwise direction as viewed in Figure 2. When the lens holder head 20 is held against rotation in a counter clockwise direction, as, for example, when the lens 15 is in engagement with a grinding wheel, the gear 130 which is operated from gear 132 serves to rotate the gears 39 and so rotates the lens. The lens holder head, however, is free to rotate unless held by some restraining means, the rotation of the gear 130 in a counter clockwise direction serves to maintain the lens in contact with the grinding wheel. Also, when the grinding wheels have been raised to their uppermost position, they will be out of the path of the lens holder head and the lens holder head may then rotate about the axis 21' in a counter clockwise direction and will continue this rotation until stopped by some obstacle interposed in its path.

Grinding wheel shift

The grinding wheels are moved downwardly to their successive positions by means of

a cam 180. Shaft 6 is adapted to rotate and slide in a stationary bearing 181 in the table 2 and a stationary bearing 182 in the lower part of the frame 1. The lower end of the shaft 6 rotates on a thrust ball bearing 184, carried inside a hollow slidable supporting member 186, formed at its lower end with a truncated surface 187 which is adapted to be engaged by the cam 180. Cam 180 comprises a circular plate or disk 191 which is suitably mounted to rotate in a horizontal plane and also comprises a cylindrical wall 192 of varying height which projects upwardly from the plate 191 near its periphery. The upper surface of the wall 192 forms the cam surface and engages the truncated bottom surface 187 of the member 186 to permit the grinding wheels to move downwardly by gravity to their successive positions and then to raise them. The upper surface of the wall 192 is formed with four horizontal portions, corresponding to four positions of the grinding wheels and indicated by P_1 , P_2 , P_3 , and P_4 , respectively. The upper surface of the wall 192 is inclined upwardly between the portions P_4 and P_1 . When the truncated surface 187 is at position P_2 , the lens is being ground by wheel A and when at position P_3 , the lens is being ground by wheel B, and at position P_4 , by the finishing wheel C. At P_1 the grinding wheels are raised above the lens holder head and while at this position the lens holder head is rotated beneath the wheels to a position to discharge a lens which has been ground and to take on a new lens from the chute 50. While the supporting member 186 is riding up the long inclined surface between positions P_4 and P_1 , the operations of ejecting a lens and taking on a new one are performed.

Bolted to the circular cam plate 191 at its periphery is a gear 200, which is adapted to be rotated by a worm mounted on a horizontal shaft 202. Shaft 202 carries a gear 203 which is turned by a worm 204 on a vertical shaft 205. Shaft 205 is adapted to be coupled to and uncoupled from a shaft 207 which is driven from the shaft 101 through bevel gears 209 and 210, respectively. The coupling and uncoupling of the shafts 207 and 205 are effected by an electromagnetic clutch 212.

Means is provided for controlling the circuit which serves to operate the clutch 212 so as to provide for a shifting of the grinding wheels at predetermined intervals, sufficient time being allowed for each wheel to complete its grinding operation on the lens before the wheels are shifted. Also this electrical controlling means is designed to insure the stopping of the vertical movements of the wheels in positions for proper engagement with the lens.

In Figure 6 of the drawings I show diagrammatically the circuit arrangement for

controlling the actuation of the clutch 212. Reference characters 220 and 221 represent two rotary controllers or switches. Controller 220 comprises a long arcuate contact 224 and three shorter arcuate contacts 225, 226, and 227, respectively. These contacts are formed on the bottom of the rotary cam 180, as indicated in Figure 1 and rotate with the cam. Contacts 224 and 226 are located at a greater distance from the centre of rotation than are the contacts 225 and 227. Adapted to be engaged by the contacts 224 and 226 as these contacts rotate, is a stationary contact 230, and closely adjacent to the contact 230 and electrically connected therewith is a similar stationary contact 231.

The controller 221 comprises four arcuate contacts 235, 236, 237 and 238, respectively, which rotate about a centre 240. The contacts 236 and 238 are located at a greater distance from the centre 240 than the contacts 235 and 237. Adapted to be engaged by the contacts 235 and 237 as they rotate, is a stationary contact 242, and adapted to be engaged by the rotary contacts 236 and 238, is a stationary contact 243. Contacts 242 and 243 are electrically insulated from one another. The rotary contacts 235 to 238, inclusive, are formed on a gear 250, shown in Figure 1, which gear is rotated by means of a worm on a shaft 255, shaft 255 being driven from the shaft 101 through bevel gears 110, shaft 257, shaft 258, worm 259, and gear 260.

The current for energizing the magnetic clutch 212 is supplied from the mains 270 and 271, shown in Figure 6.

As shown in Figure 6, the supply main 270 is connected to the rotary contacts 235 to 238, inclusive, by a conductor 262. The main 271 is connected to both the stationary contacts 230 and 231 through conductor 264, clutch 212 and conductor 265. Extending between the two controlling switches 220 and 221 are a pair of conductors 267 and 268. Conductor 267 is connected to the stationary contact 242 of the controller 221 and this conductor is also connected to the rotary contacts 224 and 226 of the controller 220. Conductor 268 is connected to the stationary contact 243 of the controller 221 and is also connected to the rotary contacts 225 and 227 of the controller 220.

It is to be noted that the controller 221 being directly connected with the actuating shaft 101 is operated continuously while the grinding machine is in operation, whereas the controller 220, which is operated from the power shaft 101 through the clutch 212, is operated only when the clutch 212 is energized. The operation of the controlling system shown in Figure 6 is as follows, assuming that the connections between the power motor and the controllers are such as to rotate the controllers in a counter clock-

wise direction: In the position of the parts as shown in Figure 6, the grinding wheels are in their top position, that is, the end 187 of the hollow member 186 is resting on position P_1 of the cam 180. The wheels are in their raised position and while in this position the lens holder heads swing under the wheels, each discharging a lens and taking on a new lens.

It will be noted that arcuate contact 224 has just passed out of engagement with the fixed contact 230 which has resulted in breaking the circuit through the clutch 212. Segment 225 has moved into engagement with contact 231, but as the circuit through contact 225 is broken at contact 243, the clutch remains de-energized. As the controller 221 rotates, however, in a counter clockwise direction, the segment or arcuate contact 236 is finally moved into engagement with the fixed contact 243 of the controller 221. This completes a circuit through the magnetic clutch 212 by way of main 271, conductor 264, clutch 212, conductor 265, stationary contact 231, segment 225, conductor 268, stationary contact 243, segment 236, conductor 262, main 270. The energizing of the clutch 212 serves to couple the shaft 205 to the shaft 207 and starts the rotation of the cam 180 which lowers the shaft 6 and the grinding wheels until grinding wheel A comes into position for grinding the lens. This is position P_2 and is the position of the parts shown in Figure 1. During the rotation of the cam 180, controller 220 is rotated in a counter clockwise direction and as wheel A reaches its position for grinding, segment 225 of controller 220 moves out of engagement with the stationary contact 231 and the circuit through the clutch is broken. Contact 236 of controller 221 is made sufficiently long to maintain the circuit through the clutch during the time that arcuate contact 225 is moving in engagement with fixed contact 231, so that the circuit through the clutch 212 will remain closed until position P_2 of the cam is reached.

When the arcuate segment 225 has passed out of engagement with contact 231, the circuit through the clutch will remain broken until segment 237 of the controller 221 has moved into engagement with fixed contact 242, at which time a circuit will be completed again through the clutch by way of conductor 264, clutch, conductor 265, contact 230, contact 226, conductor 267, contact 237, conductor 262. This will serve to operate the cam and lower shaft 106 to position P_3 , at which grinding wheel B is operating on the lens. When the shaft reaches this position, segment 226 passes out of engagement with contact 230 and the circuit through the clutch is again broken. The cam 180 remains in this position for sufficient length of time to permit wheel B to complete its operation of grinding or polish-

ing the lens, at the end of which time segment 238 of controller 221 moves into engagement with contact 243, which serves to actuate the clutch and move the cam to position P_4 , at which position finishing wheel C is in position to operate on the lens. The grinding wheels remain in their lowermost position until segment 235 again engages contact 242, at which time, as will be readily apparent, the clutch will be again energized and the cam will be turned so as to raise the grinding wheels to position P_1 . When the grinding wheels have been raised to a sufficient height, the lens holder heads swing under them, discharge new lenses, and take on new lenses.

Lens holder movement control

At each end of the lens holder head 20 is a slide 290 which is adjustable in a transverse direction by means of a screw 291. Each slide 290 carries a roller 294 which is adapted to engage the periphery of the grinding wheel and so limit the counter clockwise rotation of the lens holder head during the grinding of the lens. Roller 294 is adjusted in its position relative to the lens holder head when it is desired to change from a lens of one diameter to a lens of a different diameter and this adjustment is also made when it is desired to change the angle of bevel to be ground at the edge of the lens, as will be more fully explained hereafter.

When the desired bevel has been ground, the wheel or roller 294 coming into contact with the grinding wheel serves to stop further advance of the lens toward the grinding wheel and so stop the grinding. As the lens is rotating about its central axis as it is being ground, the use of the roller 294 insures the formation of a beveled lens which is exactly circular in shape and this is true regardless of any wear of the grinding wheel during the grinding operation. The use of the roller 294 also insures absolute uniformity of product, each lens or disk at any one adjustment of the machine being of exactly the same shape and size as any other disk ground at the same adjustment. Also the roller 294 acts as a safety device in case the lens holder fails to take a lens from the chute 50 and then swings toward the grinding wheel. In this case roller 294, on contact with the grinding wheel, stops the motion of the lens holder and prevents the lens holder seat from coming into contact with the wheel.

When the grinding wheels have been raised to their uppermost position and the lens holder head has swung beneath the wheels, the lens holder head is automatically stopped in position to discharge the finished lens and take on a new lens. While in this position, rod 52, which operates the pistons 35, is raised and then lowered, these movements effecting the discharge of the old lens and taking on a new lens, after which operation the lens

holder head is released and permitted to turn in a counter clockwise direction into position for cooperation with wheel A.

The stopping of the lens holder head at its discharge position is controlled by a cam 300, mounted on a shaft 301, which is connected to and rotates at the same speed as gear 250. Cam 300 serves to move a connecting rod or link 304 which is pivotally secured to an arm of a spider 305. Spider 305 is formed with a hub 306 which surrounds the shaft 6. Spider 305 has four arms at the outer ends of which are lugs 310 which project upwardly through an opening 311 in the supporting table 2. By movement of the cam 300 the four lugs 310 at the outer ends of the respective arms of the spider 305 may be moved so as to project into the path of a pin 312, carried by the lens holder head, and stop rotation of the head.

It is to be noted that one revolution of the gear 250 corresponds to one complete cycle of operations of the machine and cam 300, which rotates at the same speed as gear 250 thereby makes one complete revolution during the time of a complete cycle of grinding operations. The cam 300 is formed with inclined surfaces 316 which are so positioned as to move the lugs 310 while the lens holder head is swinging beneath the grinding wheels to such a position of the lugs that they will form an obstacle in the path of the pins 312, and, after operation of the pistons 35, these surfaces 316 of the cam 300 serve to move the lugs out of the path of the pins 312 and permit the lens holder head to turn to its grinding position.

The upward and downward movement of the rods 52 which serves to operate the pistons 35 is effected by rotation of a cam 320, likewise mounted on the shaft 301. Cam 320 serves to operate an arm or link 322 connected to one arm of a spider 324. Spider 324 has four arms, the outer end of each of which is connected to an arm 327, pivoted to a sleeve or collar 328 which is mounted to rotate on an extension 329 of the fixed bearing shaft 116. Arm 327 is adapted to be rigidly secured to the sleeve 328 by a set screw 330 or other suitable means. Sleeve 328 forms one end of an arm 331, at the other end of which is formed a cam surface 335, adapted to engage a head 336, formed at the lower end of the rod 52. Arms 327 and 331 together form a bellcrank lever, which is adapted to be rotated about the axis of the bearing shaft 116. Rotation of this lever by an arm of the spider 324 in a clockwise direction as viewed in Figure 3, serves to raise the rod 52 and subsequent rotation of the bellcrank lever in a counter clockwise direction serves to lower the rod 52. Cam 320 is provided with inclined surfaces 340 which are so positioned that they effect the raising and lowering of the rod 52 at the time

when the lens holder head is in its lens discharging and lens receiving position.

I also provide means which is operative whenever the grinding wheels are shifted, for retracting the lens slightly from the wheels in order that the movement of the wheels will not injure the lens. This I accomplish by means of a cam 360, which is likewise mounted on the shaft 301. Cam 360 serves to operate an arm 362, connected at one end to a spider 363, formed with four arms at the outer ends of which are upwardly projecting lugs 365. These lugs are adapted on movement of the spider 363 in a clockwise direction, as viewed in Figure 3, to engage pins 370 carried by the lens holder head and retract the lens holder head and lens from the path of the grinding wheels as they are moved vertically.

Cams 316, 340, and 360 may be angularly adjustable on the shaft 305, so as to vary their setting if occasion requires. It will of course be understood that the circuit through the clutch may be interlocked with the cam 360 so as to insure the closing of this circuit only in case the lens has been retracted from the grinding wheel, thus insuring that the vertical movement of the wheels will occur only when the lens has been retracted.

Adjustments for grinding bevels of different angles

The bearing sleeve 125 which supports the lens holder head is adjustable to different positions in the arcuate slot 126 so as to vary the angle of bevel ground at the edge of the lens. In changing the position of the lens holder head in this manner, arm 123 is rotated about the stationary bearing shaft 116 and suitable means may be employed for rigidly holding the arm 123 in its adjusted position, such, for example, as a thumb screw 380 threaded through the sleeve 122 and bearing against the upwardly projecting portion of the shaft 116.

In Figure 2 I show each lens holder assembly in a different position for grinding a different bevel, that of the lens holder assembly 13 being in position to grind a bevel of zero angle, that of assembly 12, a somewhat greater angle, that of assembly 11, a still greater angle, and that of assembly 10, a yet greater angle, the last approximating a bevel of 45°. While I have shown the different lens holder heads at different angular positions, it will be understood that all four lens holder heads may be positioned at the same angle relative to the outer edge of the grinding wheel.

A number of adjustments are required for different set positions of the lens holder assembly, corresponding to different angles of bevel, so as to insure a proper contact of the lens and the grinding wheel and to provide

for the movement and stopping of the lens holder head at proper times during the cycle of operations.

To provide for the proper contact of the lens with the grinding wheel at different bevel adjustments, the screw 291 is employed to move the roller 294 transversely of the lens holder head. To provide for a proper setting of the cam 335 at different bevel adjustments, the angular position relative to one another of the arms 327 and 331, which form the bellcrank lever operated by spider 324, is changed; this being accomplished by loosening the set screw 330, adjusting the angle between the arms and then tightening the set screw.

To provide for the proper operating engagement between the lugs 310 carried by the spider 305 with the pins 312 carried by the lens holder heads, the pins 312 are adjustable along their respective arcuate slots 390, formed in the lens holder heads. Similarly to provide for proper engagement between the lugs 365 of the pins 370 at different bevel settings, the pins 370 are adjustable in arcuate slots 392 in the lens holder heads.

It will be understood, of course, that each lens holder head is provided with two pins 312 and two pins 370, located at opposite sides of the shaft 22, and these will each be adjusted when the angle of bevel is changed.

The finishing grinding wheel

Grinding wheel C, which performs the finishing operation on the lens, preferably has a working or polishing surface, formed by a strip of felt carried by the periphery of the wheel. In Figures 7 and 8 I show one preferred form of finishing wheel, which comprises a body 400, formed at its periphery with a series of recesses 401, having walls which curve outwardly. The polishing surface of the wheel is formed of a strip of felt 404, which is held to the outer surface of the body by means of clamping bars 405, which may be forced into the recesses by clamping screws 407.

Between two successive recesses 401 the outer or active surface of the felt is held in substantially cylindrical form between the points 408 and 409, that is, the felt follows a circle having as its centre the centre of rotation of the wheel. From the point 409 to the next succeeding recess 401 to the left the inward curvature of the felt strip increases progressively toward the bottom of the recess to the left and thence curves outwardly at the other side of the recess. The purpose of this configuration of the operating surface of the finishing wheel is to cause the wheel not only to finish off the bevel surface of the lens over its entire width, but also to round off the acute angle at the junction of the bevel surface and one side of the lens, so that angle will not be sharp. The action of the wheel in rounding off the angle

is apparent from Figure 7 of the drawings in which for the purpose of illustration I have shown by dotted lines at 410 and 412, positions of the lens with respect to the felt strip as the wheel rotates in the direction indicated by the arrow. It will be seen that in position 410 the felt strip is in contact with the acute angle between the bevel surface and one face of the lens, the lens being pressed against the felt at this point by the lens holder which is urging the lens toward the wheel.

Due to the fact that the felt between the point 409 and the recess at the left of Figure 7 follows a curve which is inclined toward the axis of the grinding wheel, the roller at the time the lens is in position 410 is out of contact with the grinding wheel, as is shown in dotted lines in Figure 7, thus permitting the lens holder head to press the acute angle of the lens against the inclined wall of the recess 401. The roller, however, prevents any extensive movement of the lens into the recess and avoids contact of the lens with and damage by the bars or wedges 405. If desired, I may also keep the roller 294 out of contact with the wheel C by making this wheel of somewhat greater diameter than the wheels A and B, the roller being adjusted for normal operation with the wheels A and B. In this case, however, lug 363 should be so formed as to retract the lens from each of the three wheels as the wheels are shifted.

It will be understood that suitable means will ordinarily be employed for supplying water to the grinding surfaces of wheels A and B during the grinding operation.

While in the above description I have generally referred to the work being operated upon as lenses, it will be understood that such term includes watch glasses or other glass disks and similar glass objects.

Having now described my invention, what I claim and desire to secure by Letters Patent, is:

1. In a disk beveling machine, a grinding wheel, a disk holder, means for feeding a disk to said holder, means for moving said holder so as to move the edge of said disk into grinding engagement with said wheel, means for rotating said disk while in engagement with said wheel, and means for releasing said disk from said holder after the grinding operation is completed.

2. In a disk beveling machine, a grinding wheel, a disk holder, means for feeding a disk to said holder, means for moving said holder so as to move said disk into grinding engagement with said wheel, means for rotating said disk while in engagement with said wheel, means for releasing said lens from said holder after the grinding operation is completed, and means for adjusting the machine so as to vary the angle of bevel.

3. In a lens beveling machine, a plurality of

grinding wheels mounted on a shaft, a lens holder having means for pressing a lens into grinding contact with one wheel, means for temporarily withdrawing the lens from contact with said wheel and means for shifting said wheels while said lens is withdrawn so as to bring a second wheel into position for grinding contact with said lens.

4. In a lens beveling machine, a plurality of grinding wheels, means for rotating said wheels, a lens holder having means for pressing a lens into grinding contact with a wheel, means for temporarily withdrawing the lens from a wheel and means for shifting the wheel while said lens is withdrawn so as to bring another wheel into position for grinding contact with said lens.

5. In a machine of the character described, an inclined lens supply chute open at the bottom, yieldably releasable lens restraining means at said bottom, a suction operated lens holder and means for advancing said lens holder into contact with a lens at the bottom of said chute, creating suction to hold said lens and withdrawing said holder and lens from said chute.

6. In a machine for beveling lenses, a grinding wheel, an inclined lens supply chute open at the bottom, yieldably releasable lens restraining means at said bottom, a lens holder having a suction nozzle, means for advancing said nozzle into engagement with the face of a lens held at the bottom of said chute, for applying suction to hold said lens and subsequently withdrawing said nozzle and lens from said chute and means for moving said nozzle toward said wheel whereby said lens is brought into grinding contact with said wheel.

7. In a disk grinding machine, a grinding wheel, a rotatable disk holder head having two disk holders, supply and discharge receptacles, and operating and controlling means for causing one of said holders to receive a disk from said supply receptacle and discharge a disk to said discharge receptacle and for subsequently rotating said head so as to move said former disk into grinding contact with said wheel.

8. In a grinding machine, a grinding wheel, a rotatable disk holder head having two disk holders comprising suction means for operating the holders to receive and discharge a disk, supply and discharge receptacles and controlling means for causing one of said disk holders to receive a disk from said supply receptacle and discharge a disk into said discharge receptacle and for subsequently rotating said head so as to move said former disk into grinding contact with said former wheel.

9. In a grinding machine, a grinding wheel, a rotatable disk holder head having two disk holders, supply and discharge re-

ceptacles and electrical operated means for causing one of the disk holders to receive a disk from said supply receptacle and to discharge a disk to said discharge receptacle and for subsequently rotating said head so as to move said former disk into grinding contact with said former wheel.

Signed at New York in the county of New York and State of New York this first day of August A. D. 1929.

CHARLES V. WALTER.
